INVENTOR.

Louis O. French.

UNITED STATES PATENT OFFICE.

LOUIS O. FRENCH, OF MILWAUKEE, WISCONSIN.

INTERNAL-COMBUSTION ENGINE.

Application filed May 29, 1924. Serial No. 716,687.

The invention relates to internal combustion engines, and more particularly to those using liquid fuel.

In engines which are now quite commonly known as gas injection type internal combustion engines, the passage of fuel from the fuel-receiving chamber cannot be readily controlled, and especially those engines in which the fuel in a liquid state is introduced into a fuel-receiving chamber during the suction stroke of a four-cycle engine, or during the scavenging period of a two-cycle engine. The object of this invention is to provide an internal combustion engine of the gas injection type of improved construction over those heretofore known, by delaying the introduction of the fuel charge into the cylinder after its passage from the fuel-receiving chamber, and to mix the main fuel charge with gas as it passes to the cylinder, and to utilize some of the fuel charge either under conditions of constant volume combustion or mixed combustion to assist in the expulsion of the charge to the cylinder, the action of the gas assisting in vaporizing such fuel as may issue from the fuel-receiving chamber in a liquid state.

A further object of the invention is to provide a gas injection type engine that may be run on more volatile fuels, such as gasoline or its substitutes, than are usually employed with engines of this general type, and under medium or low compression pressures, with such provision for stratification of the fuel charge as to prevent detonation and secure efficient combustion at constant volume.

The invention further consists in the several features hereinafter set forth and more particularly defined by claims at the conclusion hereof.

In the drawings: Fig. 1 is a vertical sectional view taken on the line 1—1 of Fig. 2 through an engine embodying the invention;

Fig. 2 is a plan view of the cylinder head and associated parts.

In the drawings the numeral 3 designates the cylinder of the engine, 4 the piston working therein, 5 the cylinder head with the waterjacket space 6, 7 the main combustion chamber, 8 a fuel-receiving chamber, 9 a gas chamber, 10 a mixing passage with which chambers 8 and 9 communicate, 11 a fuel-control valve, 12 the main air inlet valve,

and 13 the exhaust valve, said last-named valves being used where the engine is four-cycle.

The fuel-control valve 11 is mounted in a plug 14 having screw-threaded engagement with the cylinder, a pipe threaded connection being here shown, to permit ready removal of the plug from the cylinder and providing a seal when mounted in the cylinder head. The valve 11 controls the passage of fuel from a duct 16 in the plug to the chamber 8. The duct communicates with a passage 17, the flow of fuel from the passage 17 to the passage 16 being controlled by an adjustable needle valve 18 having screw-threaded engagement with the upper end of the plug, and either manually or governor-operated. The duct passage 17 is supplied with fuel from a fuel tank, not shown, through a pipe 19 connected with said tank, said fuel being either under gravity head or under a slight pressure head from gas pressure in the tank.

The inlet and exhaust valves are of well-known construction normally closed by springs 20 and opened by suitable valve gear such as tappet levers 21 operated by push-rods 22 from a half-time cam shaft, not shown.

The fuel-control valve 11 also preferably controls passage of some air into the chamber 8 from a passage 23. In case of a four-cycle engine this duct leads to atmosphere, as shown, and in a two-cycle engine it may connect with the scavenging air supply. This valve is normally held closed by a spring 24 and may be of the automatic inlet type, opened either by suction pressure in the four-cycle or by the scavenging pressure in a two-cycle engine. It may also be positively operated during the suction stroke of the four-cycle or the scavenging stroke of a two-cycle engine by a suitable valve mechanism of any well-known form of overhead valve gear. As shown, in connection with the four-cycle engine, the valve is actuated by a lug 25 on the tappet lever 21 for the inlet valve with a screw 26 on said lug and engageable with the valve and adjustable relative to said lug to permit relative adjustment between the lever and said valve to vary the timing operation of the valve 11 relative to the inlet valve 12, if desired.

The chamber 8 is in restricted communication with the passage 10 and preferably

at the upper end thereof through one or more passages 27, preferably relatively small but not necessarily so fine as to be relied upon for atomizing purposes since the 5 action of the gas in the mixing passage causes a breaking up of the fuel charge should some of it issue from the chamber 8 in a liquid state.

The end of the passage 10 is preferably in 10 restricted communication with the combustion chamber through one or more openings 28, though in some instances said end may be left in open communication with the chamber 7. As shown, the openings 27 and 15 28 are formed in a tube 29 having a close fit with the adjacent walls of the head, to prevent excessive heating, and a threaded connection with said head at its lower end. The passage 10 throughout its length, as 20 well as its lower end, may be water-cooled, if desired. The passage 10 may take the form of a Venturi passage with the passages 27 introducing the fuel charge into the throat portion thereof, as shown, said throat being 25 preferably located adjacent the chamber 9.

Where volatile fuel is used as the main fuel or as a starting fuel for the engine, a 30 sparking ignition device 30 is mounted in the chamber 9. Where less volatile fuels are used an incandescent ignitor of the hot 35 surface or hot electric wire type may be used either in the chamber 8 or the chamber 9, or a portion of the surface of the chamber 9 may be uncooled.

The chamber 9 is here shown formed as a 40 part separate from the cylinder head and bolted thereto, and said part is also recessed and forms with the tube 27 and a part of the main cylinder head the chamber 45 8, though said chambers 9 and 8 may be formed integrally with the cylinder head, if desired.

Assuming that the engine has been started and a volatile fuel is being used, during a 45 period of low pressure in the engine cylinder, that is during the suction stroke of a four-cycle or the scavenging period of a two-cycle engine, the valve 11 is opened allowing fuel to flow from the duct 16 to the 50 chamber 8, as well as some air from the passage 23. During the suction stroke some 55 of the fuel in a gaseous state, due to its contact with hot gases from a previous cycle and its mixing with the air let in through passage 23 when such passage is provided, may be drawn into the passage 10 where it 60 contacts with more inert exhaust gases and during the compression stroke is forced up into the chamber 9 while the remainder of the fuel is in the chamber 8. As compression 65 proceeds air from the cylinder is forced up into the passage 10 and into the chambers 8 and 9 and near or at the end of the compression stroke when an explosive mixture has been formed in the chamber 9 the spark from

the ignition device 30 ignites said mixture and the consequent explosion builds up a pressure therein, due to the restricted outlet, greater than that in the main combustion chamber, and as the hot flaming gases from the chamber 9 pass down through the passage 10 at relatively high velocity, they encounter fuel coming in from the chamber 8 and mix and pass therewith through openings 28 into the main combustion chamber as the piston starts on its downward stroke. Thereafter combustion of the fuel charge introduced into the air in the cylinder becomes general with the 70 expanding gases driving the piston downward on its power stroke. Furthermore, the suction effect of the piston accentuates the difference in pressure between the main combustion chamber 7 and the other parts 8, 9 and 10 and acts to draw the fuel from the chamber 8 into the hot gases from the chamber. This last condition may be especially the case with a two-cycle engine, as there may be only a small amount of fuel that reaches the chamber 9 during the compression stroke. However, in either case the building up of pressure in the chamber 9 by the burning of gases therein causes some of the hot gases issuing therefrom to enter the chamber 8 and act to vaporize or 75 gasify the fuel therein, and should the expansion of the gases in the chamber 8 drive some of the fuel in a liquid state into the passage 10, the hot gases coming from the chamber 9 will act to vaporize such liquid fuel, either completely or to a great extent, before its passage to the cylinder.

The advantage of the restriction between the passage 10 and the main combustion chamber is that it permits the ready retention of relatively inert gases in the chamber 9 and passage 10 and thereby retards active combustion until late in the compression stroke, and it also retards the relatively free passage of air to the chamber 9 during the 100 compression stroke to thereby retard active combustion until desired, and it also aids the mixing action and distribution of the fuel charge into the air in the main combustion chamber.

Thus, in the case of a volatile fuel using low or medium compression pressures, the fuel introduced into the chamber 8 before compression begins is vaporized and mixed with air and heated by inert gases before 110 passing into the main combustion chamber near or at the end of the compression stroke. With medium compression pressures less volatile fuel may be used after the engine has become heated, because then the air undergoing compression is itself brought to a higher temperature and serves to break down some of the lighter constituents of the fuel in the chamber 8 which acts as a volatile fuel charge in the manner previously described, 115 120 125 130

and upon the remainder of the fuel to gasify and discharge it into the cylinder at or near the beginning of the working stroke.

When high compression pressures are used the heat of the air alone is used to effect a gasification of some of the fuel in the chamber 8. As said chamber 8 is water-cooled, for the most part, gasification of the fuel will not be as rapid as in engines here-
10 tofore known so that there is less danger of detonation occurring in the main combustion chamber, such fuel as is gasified, however, acting in the manner of the volatile fuel, as previously described, to vaporize, expel and
15 mix the remainder of the fuel charge and discharge it through the passage 10 and openings 28 into the main combustion chamber at or near the beginning of the working stroke.

20 The inlet and discharge of air and exhaust gases from the cylinder space takes place through the valves 12 and 13 in the usual manner, and through valves or ports in a two-cycle engine in any suitable manner.

25 It will also be noted that the rate of passage of the fuel charge from the chamber 8 into the passage 10 may be regulated by selection of the proper discharge area provided by the hole or holes 27, and that the
30 amount of gaseous fuel to the amount of air or other gas passing through the passage 10 may be determined by the rate of discharge from the chamber 8 and the cross-sectional area of the throat portion of the passage 10.

35 The construction above described permits of a gradual mixing of the fuel charge with the gas passing to the cylinder, and this permits of a proper proportion of fuel to air at different loads, and a mixture may be
40 formed at light loads and efficiently consumed in an excess of air.

I desire it to be understood that this invention is not to be limited to any particular form or arrangement of parts except in so far as such limitations are included in the claims or necessitated by the prior art.

What I claim as my invention is:—

1. In an internal combustion engine, the combination with the cylinder space, of a fuel-receiving chamber, a gas chamber, a mixing passage constantly communicating with said gas chamber and in continual direct restricted communication with said fuel-receiving chamber and leading to said cylinder space, means for supplying air to said cylinder space, and means distinct from said first-mentioned air supply means for introducing fuel into and supplying air to said fuel-receiving chamber before compression begins.

2. In an internal combustion engine, the combination with the cylinder space, of a fuel-receiving chamber, a gas chamber, a mixing passage constantly communicating

with said gas chamber and in continual direct restricted communication with said fuel-receiving chamber, said mixing passage extending to said cylinder space, a nozzle member at the inner end of said mixing passage, means for supplying air to said cylinder space, and means distinct from said first-mentioned air supply means for supplying fuel and air to said fuel-receiving chamber before compression begins. 65

3. In an internal combustion engine, the combination with the cylinder space, of a fuel-receiving chamber, a gas chamber having a Venturi discharge passage leading therefrom to the cylinder space, said fuel-receiving chamber having a discharge passage in communication with the throat portion of said Venturi passage, means for supplying air to said cylinder space, and means distinct from said first-mentioned air supply means for supplying fuel and air to 80 said fuel-receiving chamber before compression begins. 85

4. In an internal combustion engine, the combination with the cylinder space, of a fuel-receiving chamber, a gas chamber having a Venturi discharge passage leading therefrom to said cylinder space, a discharge nozzle at the inner end of said passage, said fuel-receiving chamber having a discharge passage in communication with the throat portion of said Venturi passage, means for supplying air to said cylinder space, and means distinct from said first-mentioned air supply means for supplying fuel and air to 95 said fuel-receiving chamber before compression begins. 100

5. In an internal combustion engine, the combination with the cylinder space, of a fuel-receiving chamber, a gas chamber, a mixing passage constantly communicating 105 with said gas chamber and in continual direct restricted communication with said fuel-receiving chamber and leading to said cylinder space, and means including a valve opening inwardly into said fuel-receiving chamber for controlling the passage of fuel thereto. 110

6. In an internal combustion engine, the combination with the cylinder space, of a fuel-receiving chamber, a gas chamber, a mixing passage constantly communicating with said gas chamber and in continual direct restricted communication with said fuel-receiving chamber and in communication with said cylinder space, a discharge 115 nozzle at the inner end of said passage, and means including a valve opening inwardly into said fuel-receiving chamber for controlling the passage of fuel thereto. 120

In testimony whereof, I affix my signature. 125

LOUIS O. FRENCH.
